United States Patent Office.

PHINEAS JONES, OF NEWARK, NEW JERSEY.

Letters Patent No. 67,768, dated August 13, 1867.

IMPROVEMENT IN DRIVING-REINS.

The Schedule referred to in these Letters Patent and making part of the same.

TO ALL WHOM IT MAY CONCERN:

Be it known that I, PHINEAS JONES, of Newark, in the county of Essex, and State of New Jersey, have invented a new and improved Holder for Reins; and I do hereby declare that the following is a full, clear, and exact description thereof, which will enable others skilled in the art to make and use the same, reference being had to the accompanying drawings, forming part of this specification.

The object of this invention is to provide a simple device whereby harness-reins may be securely held, and will effectually be prevented from slipping out of the hand. This invention will prove of especial value in winter, when the driver's hands, either from the effects of the frost or by the large gloves, are prevented from securely handling or holding the reins. In the annexed drawing, my invention is illustrated—

Figure 1 being a perspective view of my improved rein-holder, and

Figure 2 a side view of the same.

Similar letters of reference indicate like parts.

A is the holder, which is made of any suitable kind of bar or other metal, or of any other suitable material, and of any suitable length, being generally from three to four inches long. The central part *a* of the holder is round, as shown in the drawings, while both ends *b* are flattened. The whole may then be covered with leather, or any other suitable material. The rein B is provided with button-holes *c*, as shown, through which the flat end is passed until the central piece *a* is in the hole, then the holder is turned so that the broad face of its ends stands at right angles with the button-hole. The holder is then secure and cannot drop off the rein, while it can be easily removed, if desired. This holder, projecting on both sides of the rein, is a very secure handle for the same.

What I claim as new, and desire to secure by Letters Patent, is—

As a new article of manufacture, a rein-holder consisting of the bar A, having its ends *b* flattened, its centre *a* rounded, and the whole covered with leather and inserted in the button-hole *c* of the rein B, substantially as herein shown and described.

PHINEAS JONES.
